LIFE SAVING APPARATUS FOR SUBMARINES

José Dolores Salaverria, Salcoatitan,
San Salvador

Application April 22, 1933, Serial No. 667,439½

3 Claims. (Cl. 114—16.5)

This invention relates to a life saving apparatus for submarines, and it is primarily an object of the invention to provide an apparatus of this kind to admit in an emergency air within a submarine when in submergence.

It is also an object of the invention to provide an apparatus of this kind including a flexible hose line in communication within a submarine together with means carried by the submarine for normally maintaining the hose line in compacted form and wherein means are also provided for raising the outer end portion of the hose line to the water surface so that the interior of the submarine may be placed in communication with the atmosphere and thus prevent asphyxia of the crew in the event the vessel is incapable of rising to the water surface.

The invention also has for an object to provide an apparatus of this kind including a valve structure arranged at the outer extremity of the hose line together with buoyant means for raising said valve structure above the water surface, said valve structure when in this position having means to effect the opening of such structure for the flow of air therethrough and through the hose line to a submarine in submergence.

The invention consists in the details of construction and in the combination and arrangement of the several parts of my improved life saving apparatus for a submarine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a somewhat diagrammatic view partly in elevation and partly in section illustrating an apparatus constructed in accordance with an embodiment of my invention;

Figure 2 is a fragmentary detailed view partly in section and partly in elevation illustrating the portion of the gearing for driving the reel;

Figure 3 is a view in top plan of the valve structure as herein embodied;

Figure 4 is an enlarged vertical sectional view taken through the valve structure as herein disclosed with certain of the parts in elevation;

Figure 5 is a view in bottom plan of the structure illustrated in Figure 4 with certain of the parts omitted.

As disclosed in the accompanying drawings, D denotes the deck of a submarine upon which is rotatably mounted a reel R. This reel R rotates with a shaft 1 which is rotatably supported by the bearing standards 2 suitably mounted upon the deck D. Winding upon the reel R is a flexible hose line H, the inner extremity of which being in communication in a conventional manner with a hollow portion of the shaft 1. This hollow portion of the shaft 1 is in communication through a pipe line 3 with the desired pump (not shown) within the submarine and which pump when in operation operates to draw air through the lines H and 3 and discharge the same within the boat. As any preferred type of pump can be used it is not believed necessary that the same be described and illustrated.

An end portion of the shaft 1 has freely mounted thereon a worm wheel 4, said wheel having a clutch face 5 for coaction in a well known way with the clutch member 6. This clutch member 6 is keyed to the shaft 1 for rotation therewith but free to have movement lengthwise thereof so that the member 6 as desired can be shifted into or out of clutching engagement with the face 5 of the worm wheel 4. Operatively engaged with the member 6 in a conventional manner is a throw lever 7 and this lever 7 is operatively connected through the medium of a rod 8 with an operating member 9 suitably positioned within the vessel. As particularly illustrated in Figure 1 of the accompanying drawings, it is to be noted that by pulling down on the member 9 the clutch member 6 may be disengaged from the clutch face 5 of the worm wheel 4 and vice versa.

Meshing with the worm wheel 4 is a worm 10 carried by a shaft 11. This shaft 11 extends within the submarine and is in operative connection, as at 12, with a drive shaft 14. As disclosed in Figure 1, this drive shaft 14 is comprised within an electric motor E although it is to be stated that this shaft may be driven in any desired manner.

The outer extremity of the hose line H constitutes a rigid section 15 of desired length and threaded upon the outer or free end portion thereof is a valve casing 16 of desired dimensions and configuration. The outer extremity of this rigid portion or section 15 extends a slight distance within the housing or casing 16 as is particularly illustrated in Figure 4. Disposed over this inner or inserted end of the pipe section 15 is a guard or deflector 17 herein disclosed as conoidal in form with its apex upwardly disposed.

100

95

105

110

This guard or deflector 17 is positioned directly below an opening 18 provided in a septum or partition wall or plate 19 intersecting the housing or casing 16, the wall of said opening 18 constituting a seat for a valve member 20. The valve member 20 is carried by the lower end portion of a stem 21 which extends upwardly and is slidably disposed through the top wall 22 of the housing or casing 16. As illustrated in Figure 4 this top wall 22 is comprised within the removable head or cap for the housing or casing 16.

The upper or outer end portion of the stem 20 is flattened, as at 23, and is positioned between the inner lapping portions of a pair of rock arms 24, said flattened portion 23 and lapping portions of the arms 24 being pivotally connected by a pin 25. The overlapping portions of the arms 24 are each provided with an elongated slot 26 through which the pin 25 is directed and thus permitting the desired functioning of the parts.

The rock arms 24 are each pivotally held, as at 27, by the upwardly and outwardly disposed brackets 28 carried by the top wall 22 of the casing or housing 16. The pivoted end portions of the arms 24 are continued by the angularly related elongated arms 29, the free extremities of which carrying the floats or buoyant members 30.

The peripheral or side wall of the housing or casing 16 above the septum or partition wall 19 is provided therearound with a series of inlet openings 31. When the housing or casing 16 is in submergence the floats or buoyant members 30 will rise and be maintained in their upper portions and thus hold the valve 20 in closed position upon its seat 18. However, as the casing or housing 16 is raised above the surface of the water the members 30 will drop resulting in upward throw of the arms 24 raising or moving the valve member 20 into open position, thus allowing air to pass through the openings 31 and 18 within the casing or housing 16 below the septum or partition wall 19 and then through the hose line 15 into the submarine. This discharge of air is particularly facilitated by operation of the pump hereinbefore referred to.

It is to be noted that the septum or partition wall 19 is substantially conoidal in form and this is of particular advantage as it assures the immediate draining out of the casing or housing 16 of water therein above said septum or partition wall when the casing or housing rises above the water surface. This formation of the septum or partition wall 19 also minimizes the liability of water passing through the opening 18 during the period the apparatus is in operation.

However, to provide for the release of any such water which may collect within the lower portion of the housing or casing 16 I have in communication therewith through the bottom of the housing or casing 16 a drain pipe 32 the lower or free portion of which being returned to provide an upstanding part or leg 33. This upstanding part or leg 33 is provided with an internal valve seat 34 with which coats a ball valve member 35 whereby retrograde flow through the pipe 32 is prevented yet readily permitting discharge of the major portion of the water that may collect within the lower part of the housing or casing 16. The upstanding part or leg 33 of the drain pipe 32 has engaged therewith a cap member 36 for maintaining the ball valve member 35 in working position.

Mounted upon the rigid portion or section 15 of the hose line H is a hub sleeve 37, the same being maintained in desired position upon the

pipe section 15 by the collars 38 or the like clamped to said section 15 above and below the hub sleeve 37. The means for holding the collars 38 to the section 15 may be as preferred. As herein disclosed this is accomplished by the binding screws 39.

Radiating from the hub sleeve 37 is a plurality of spokes 40, the outer end portions of which being suitably secured to the inner wall 41 of an annular float member F of desired dimensions and configuration. As is clearly illustrated in Figure 1, the hub sleeve 37 and the spokes 40 are housed within the central opening defined by this float member F.

The top wall 42 of the member F has secured thereto a plurality of bracing arms 43 which are disposed upwardly in convergence towards the pipe section 15 and secured to a sleeve 44 mounted upon said pipe section 15. As herein disclosed this sleeve 44 is maintained in desired position by the collars 45 keyed, as at 46, to said pipe section 15 above and below the sleeve 44.

Under normal conditions the hose line H is wound upon the reel R as illustrated in Figure 1, but in the event of an emergency, as the failure of the submarine to rise, a member of the crew will pull the operating member 9 to shift the clutch member 6 into release position whereupon the buoyant member or float F together with the buoyant members 30 will carry the hose line upwardly to the water surface and the float F will cause the housing or casing 16 to be projected above such surface. As the housing or casing 16 passes above the water surface the dropping of the members 30 will result in the opening of the valve 20 so that upon operating of the pump within the vessel air will be drawn within the submarine and thus prevent asphyxia.

When it is desired to return the apparatus to its normal adjustment the operating member 9 is moved upwardly toward the deck D to throw the clutch member 6 into engagement with the clutch face 5 of the worm wheel 4 whereupon the motor E or the like is caused to operate to effect a rotation of the shaft 1 which will result in the desired winding of the hose line upon the reel R.

It is to be further stated at this time that should any water pass down through the opening 18 of the septum or partition wall 19 the same will be thrown to one side by the deflector or guard 17, thus further reducing the liability of water entering the hose line H.

From the foregoing description it is thought to be obvious that a life saving apparatus for a submarine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In a life saving apparatus for a submarine, a valve casing adapted for connection to the outer end portion of a hose line leading to the interior of the submarine, a partition intersecting said casing and having an opening, inlet openings in the wall of the casing above the partition, a valve member for closing the opening in the partition, rock arms carried by the valve casing and opera-

tively connected to the valve member, and buoyant members operatively carried by the rock arms, said buoyant members operating by their rising movements to maintain the valve member in 5 closed position.

2. In a life saving apparatus for a submarine, a valve casing adapted for connection to the outer end portion of a hose line leading to the interior of the submarine, a partition intersecting said 10 casing and having an opening, inlet openings in the wall of the casing above the partition, a valve member for closing the opening in the partition, rock arms carried by the valve casing and operatively connected to the valve member, buoyant 15 members operatively carried by the rock arms, said buoyant members operating by their rising movements to maintain the valve member in closed position, said partition being substantially conoidal in form with the opening in the parti-

20

tion positioned above the lower ends of the openings in the wall of the casing, and a drain in communication with the casing below the partition.

3. In a life saving apparatus for a submarine, a valve casing adapted for connection to the outer end portion of a hose line leading to the interior of the submarine, a partition intersecting said casing and having an opening, inlet openings in the wall of the casing above the partition, a valve member for closing the opening in the partition, rock arms carried by the valve casing and operatively connected to the valve member, buoyant members operatively carried by the rock arms, said buoyant members operating by their rising movements to maintain the valve member in closed position, a drain pipe in communication with the valve casing below the partition, and a non-return valve within said drain pipe.
